PIPE WRAPPING MACHINE

Clyde T. Lloyd, Los Angeles, Calif., assignor to
Crane Co., Chicago, Ill., a corporation of Illinois

Application January 16, 1933, Serial No. 651,924

2 Claims. (CL 242—11)

This invention relates to pipe wrapping machines of the type in which the pipe is supported between a head stock and a tail stock and rotated thereby while the covering is applied by means of a carriage moved alongside of the pipe in a direction parallel to the axis thereof and at a predetermined speed relatively to the speed of rotation of the pipe.

It is the purpose of this invention to provide such a machine having relatively few parts and which is fully automatic and capable of handling pipes of various diameters and lengths which may apply any desired number of layers of covering, which is rapid in operation and which may be controlled by one central point thereby reducing the amount of labor necessary to operate the machine.

In accordance with this invention, the length of pipe to be covered is supported between a relatively stationary head stock and an adjustable tail stock. A traveling carriage for the covering materials is provided which moves in a direction parallel to the axis of the pipe and upon which is mounted one or more rolls of covering material, together with a reservoir for the fluid covering material. Preferably the carriage also includes a control platform for the operator and the necessary controls whereby rotation of the pipe and linear movement of both the tail stock and carriage are controlled, thus necessitating only one operator for the entire machine after the pipe is placed in position.

To obtain the maximum speed and output from the machine, a driving mechanism which, for simplicity, preferably operated by a single motor for both the carriage and head stock, is so arranged that the carriage returns to initial or starting position at a much greater speed than its movement in covering direction.

A better understanding of my invention will be apparent from the following description given in connection with the drawings, in which:

Fig. 1 is a side elevation of the entire machine, certain portions of the tracks being broken away to permit illustration of the entire machine.

Fig. 2 is an enlarged side elevation of the head stock and driving mechanism omitting the face plate.

Fig. 3 is a plan view of the head stock omitting the face plate.

Fig. 4 is an end elevation of the head stock and driving mechanism omitting the face plate.

Fig. 5 is an end elevation of the carriage.

Fig. 6 is a plan view of the carriage.

Fig. 7 is a side elevation of the carriage.

Fig. 8 is a plan view of the tail stock.
Fig. 9 is a side elevation of the tail stock, and
Fig. 10 is a vertical section through the tail stock taken approximately on line 10—10 of Fig. 9.

As previously stated, the machine is adapted to support a length of pipe between the head stock and tail stocks, the former of which also rotates the pipe. The carriage travels alongside the pipe throughout substantially its entire length and lays one or more layers of paper and/or liquid covering material upon the pipe as it is rotated by the head stock.

Considering first the head stock and driving mechanism, and with particular reference to Figs. 1, 2, 3 and 4, the entire machine is supported upon a pair of I-beams 1 to which is secured the head stock indicated generally by 3, by means of a pair of base-rails 5 secured to the beams 1 in fixed relation thereto adjacent one end thereof. A pair of end frames 7 extending upwardly from the I-beams 1 supports a hollow stationary shaft 9 in which the head stock shaft 10 is journaled and which carries upon one end a face plate or center piece 11 designed to enter the end of the length of pipe 12 (Figs. 1 and 6) and support the same. The other end of shaft 10 carries a sprocket 13 by means of which shaft 10 may be rotated to rotate the pipe.

Power for rotating the head stock and also the carriage, to be later described, is supplied from a single reversible motor 14 driving a Reeves variable speed drive 15 which terminates in a main drive shaft 16 extending longitudinally along the base of the head stock. Sprocket 13 is driven from shaft 16 by a chain 17 passing over sprocket 13 and a sprocket 18 secured to the free member of clutch 19 having its fixed member keyed to shaft 16. The free member is driven in what will be termed normal driving direction.

The carriage is also driven from motor 14 and shaft 16 by the following transmission gearing. The normal drive is through gear 19^a (Figs. 3 and 4) on shaft 16, gear 20 on intermediate shaft 21 which drives a second intermediate shaft 22 carrying a friction clutch 23 through gears 24. Shaft 22 drives shaft 25 through change gears 26 which latter shaft drives a cross shaft 27 through bevel gears 28. Shaft 27 in turn drives the final drive shaft 29 through a second set of change gears 30.

The reverse drive for returning the carriage does not go through gears 19^a and 24 but through gears 31 and 32, the former being secured to the free element of a second one way clutch 33 hav-

ing its other element fixed to shaft 16 and arranged so that the free element and gear 31 is not driven upon rotation of shaft 16 in normal driving direction. In reverse direction, however, clutch 33 drives gears 31 and 32 thereby rotating shaft 22, clutch 23 being disengaged whereby change gears 26 drive shaft 25 which in turn drives shaft 29, as previously described. Omitting gears 19, 20, clutch 23 and gears 24, causes the drive shaft 29 to be rotated at a much greater speed than when shaft 16 is rotated in the normal driving direction, the ratio of speeds being preferably about ten to one.

Friction clutch 23 is operated by a lever 34 (Fig. 2) keyed to rock shaft 35 to which is also fixed a second lever 36 actuated by a link 37 connected at one end to lever 36 and at the other end to an operating lever 38 pivoted intermediate its ends. Lever 38 is moved about its pivot in opposite directions by two electric thrusters or solenoids 39 and 41 to either engage or disengage clutch 23. The electrical actuating means are of standard construction purchasable on the commercial market and need not be described. They may be connected into the motor circuit to be operated simultaneously upon reversals of the motor or they may be wired for independent operation as will be well understood by those skilled in the art.

The head stock driving mechanism also serves to move the carriage, indicated generally by the reference character 45, and shown more particularly in Figs. 5, 6 and 7. The carriage constitutes a moving vehicle for the paper rolls or other sheet covering to be supplied to the pipe axes and for the liquid coating, generally an asphaltum or other bituminous compound. The carriage is mounted upon wheels 47 which travel upon rails 49 secured to the top of beams 1 which guide the carriage in a direction parallel to the axis of the pipe to be covered.

The carriage is provided with a frame 50 pivoted thereto about a vertical pivot to permit rotation thereabout and carries two or more spindles 51 which carry spools 53 for supporting rolls of paper 54 (Fig. 7) or other wrapping material. Friction devices 55 having hand wheels are also provided whereby the proper friction may be applied to the spools to prevent spinning thereof and insure proper feed of the paper. The carriage is also provided with a tank or reservoir 57 for the fluid covering which may be maintained at the proper temperature by any suitable heating devices, not shown. The fluid is forced up into pipe 59 (Fig. 6) and through discharge nozzle 61 overhanging the pipe to be covered by means of a pump 63 preferably secured in the tank and driven by a motor 65 carried upon a platform 67 outside of the tank and secured to the carriage.

The carriage is positively moved along tracks 49 in proper timed sequence to the rotation of the pipe being covered by means of a chain 69 (Figs. 1 and 3) passing over sprocket 71 secured to shaft 29 and over a second sprocket 73 (Fig. 1) fixedly secured between beams 1 at a point to the right of any possible right hand position of carriage 45, the two ends of the chain being secured to the carriage as at 74. Rotation of shaft 29 will therefore positively move carriage 45 to the right or left, depending upon the direction of rotation of the shaft.

A tail stock, indicated generally by reference character 75, supports the other end of the pipe to be covered and is similar in many structural aspects to the head stock and comprises a truck

mounted upon wheels 77 traveling on tracks 49. The upper end of the truck is provided with a hollow stationary shaft or sleeve 79 in which is journaled the tail stock shaft 81 carrying upon one extremity a center piece or face plate 82. Shaft 81 is journaled, however, in shaft 79 for both rotary and axial movement, the shaft being urged in one direction by spring means, not shown. The truck is driven to the right or left by a torque motor 83 driving through a reduction gear 85 and pinion 87 which engages a toothed rack 89 disposed parallel to and between rails 49. The tail stock may be locked in adjusted position at any time by opening the motor circuit to motor 83 whereby the resistance of the motor to turning and the inherent irreversibility of the reduction gearing will prevent further movement of the tail stock.

A limit switch 91 is supported in position to be actuated by a cam 93 adjustably mounted upon the end of shaft 81 upon axial movement of shaft 81 after a proper tension has been placed thereon. Limit switch 91 serves to stop motor 83 and therefore retain the tail stock in position.

The entire machine is preferably controlled from the platform projecting from the carriage in order to permit a single operator to ride on the carriage and control all parts of the machine from a position where he can observe the operation of the machine. For this purpose electrical conduits or trolleys 93 and 95 fed from the head stock end are insulatingly secured to the sides of the beams 1 (Fig. 10) in position to be engaged by trolley wheels or sliding brushes 97 and 99 of the usual type carried by the tail stock and carriage. The necessary electrical control wires from the brushes are extended up through a central pedestal 101 arising from the carriage and which carries a control panel 102 on which are mounted the necessary control switches, not illustrated, by means of which the main motor 14 is started, stopped and reversed, clutch 23 controlled, the tail stock moved into and away from position and the carriage pump motor started and stopped.

The wiring necessary to obtain the desired electrical control will be understood by those skilled in the art and need not, therefore, be described in detail.

The operation of the machine is obvious from the foregoing description and may be briefly summarized as follows. The length of pipe to be covered is placed between the head stock and tail stock by suitable means, such as a crane, not shown, and the tail stock moved inwardly in position to grip the pipe between the head stock and tail stock face plates. The movement of the tail stock is automatically stopped, when the proper tension has been placed upon the tail stock shaft, by means of limit switch 91. The fluid coating may then be turned on and one or more layers of paper or other covering started around the pipe. The mechanism may then be set into motion to rotate the head stock shaft in the normal driving direction, in which direction clutches 19 and 23 are engaged and clutch 33 is free. Accordingly the pipe is rotated while the carriage is moved toward the tail stock carrying the paper and fluid coating along the pipe to cause a layer or layers of paper to be wound spirally about the pipe as the pipe is rotated. The speed of the entire machine can be controlled by the Reeves drive and the relation of movement of the carriage to the speed of rotation of the pipe can be regulated by varying either set of change

gears. After the carriage has traversed the length of the pipe, the main motor is reversed to cause reverse movement of the carriage. Clutch 23 is also disengaged to permit quick return of the carriage due to the drive being through clutch 33 and the cutting out of certain portions of the gear transmission, thus speeding up the operation of the machine. The head stock shaft being driven through one-way clutch 19 will not be rotated upon reverse movement of the carriage and consequently the pipe will not be rotated upon return movement of the carriage.

After being covered, the pipe may be covered again with one or more layers of paper by repeating the operations or it may be removed and another length of pipe substituted therefor.

From the foregoing it will be apparent that this invention provides a substantially fully automatic machine due to the three clutches, two of which, and if desired all three of which, may be automatic in operation. The machine is capable of great production due in part at least to the increased return speed of the carriage and furthermore may be controlled by one man from one vantage point.

Many other points of novelty will be obvious to those skilled in the art from the foregoing description, to whom it will also be apparent that

minor changes may be made in the details of construction of the one illustrative embodiment of this invention without departing from the spirit and scope thereof as defined in the following claims.

I claim:

1. In combination with a pipe wrapping machine having a fixed head stock provided with a rotary face plate, a tail stock movable toward and from said head stock, means including a spring arranged to urge the pipe engaging portion of the tail stock toward the head stock, and a limit switch operative upon predetermined yielding of said spring to stop the tail stock moving means.

2. In combination with a pipe wrapping machine having a fixed head stock provided with a rotary face plate, a tail stock movable toward and from said head stock, said tail stock including a pipe engaging member, a shaft on which said member is mounted and a spring normally urging said shaft toward the head stock, means including an electric motor and reduction gearing connected therewith for moving the tail stock bodily toward the head stock, and a limit switch operative upon predetermined yielding of said spring to open the driving circuit of said motor.

CLYDE T. LLOYD.
